[57] CLAIM

The ornamental design for an electronic intrusion alarm transmitter, as shown and described.

DESCRIPTION

FIG. 1 is a top front perspective view of an electronic intrusion alarm transmitter, showing my new design;
FIG. 2 is a right side elevation thereof;
FIG. 3 is a front elevation thereof;
FIG. 4 is a rear elevation thereof;
FIG. 5 is a top plan view thereof; and
FIG. 6 is a bottom plan view thereof.
